(57) **CLAIM**

The ornamental design for a mosquito killer lamp, as shown and described.

DESCRIPTION

FIG. 1 is a top, front, and right side perspective view of the mosquito killer lamp, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, and right side perspective view of the mosquito killer lamp in a handle open configuration; and,

FIG. 9 is an exploded perspective view thereof.

The broken lines in the drawings depict portions of the mosquito killer lamp that form no part of the claimed design.

1 Claim, 9 Drawing Sheets
